UNITED STATES PATENT OFFICE.

EDWIN FITTS, OF DETROIT, MICHIGAN, ASSIGNOR TO DETROIT STOKER COMPANY, OF DETROIT, MICHIGAN, A CORPORATION OF MICHIGAN.

AUTOMATIC-STOKER FURNACE.

1,242,336.

Specification of Letters Patent.

Patented Oct. 9, 1917.

Application filed October 15, 1915. Serial No. 55,950.

To all whom it may concern:

Be it known that I, EDWIN FITTS, a citizen of the United States of America, residing at Detroit, in the county of Wayne and State of Michigan, have invented certain new and useful Improvements in Automatic-Stoker Furnaces, of which the following is a specification, reference being had therein to the accompanying drawings.

10 The invention relates to furnaces of the type provided with automatic mechanism for stoking and the invention comprises various features of construction as herein-after set forth.

15 In the drawings:

Figure 1 is a perspective view of the furnace;

Fig. 2 is a front elevation thereof;

20 Fig. 3 is a sectional elevation of the motor for actuating the stoking mechanism;

25 Figs. 4, 5 and 6 are respectively a plan view, longitudinal section and front elevation of the gate-operating mechanism for the stoker.

30 Fig. 7 is a detail view of the fly-wheel.

A is the furnace front, B is the fuel door for hand feeding, C are doors to the magazine, D is the mechanism for operating the various movable parts of the stoker, such as 35 the fuel feed, clinker-bars, etc., and E is the motor for actuating said mechanism.

It is usual with furnaces of this type to provide a steam-actuated motor having a step-down gearing for transmitting movement to the stoker mechanism. Frequently the gearing or some portion thereof is exposed and the dropping of coal or other material into the gears interferes with their operation. I have therefore devised a construction of motor unit which includes not only the engine but also the step-down transmission gearing, all of the parts being housed so as to protect the mechanism from dust and dirt. The mechanism is also disposed in such a manner that the only portion projecting beyond the furnace front is the crank arm for actuating the stoker mechanism.

50 In detail, F is the engine having the pitmen G connected to a crank shaft H having a fly-wheel I at its forward end. J is a governor mounted on the crank shaft for controlling the valve mechanism K, by which the speed of the engine is regulated. L is a

worm on the crank shaft engaging the 55 worm-gear M of an intermediate shaft M', having the worm N engaging a worm-gear N' on a shaft O arranged below and parallel to the crank shaft. All of these parts are mounted upon a base or frame P, and 60 the shaft O projects beyond this frame and has secured thereto the crank Q. The step-down gearing, as well as the governor, fly-wheel and other parts of the mechanism, are all housed.

65 Where the motor is not self-starting it is necessary to provide means for starting it in case the cranks are upon dead center. Such a means I have provided, which comprises a lever R pivoted within the housing 70 S for the fly-wheel and passing outward through a segmental slot in the periphery of said housing. The fly-wheel is provided on its flange with a series of notches S' forming ratchet teeth with which the pin R' on the lever R may be engaged by a lateral deflection of said lever. Thus the operator by pressing the lever inward toward the fly-wheel can engage it with one of the ratchets 75 to rotate the wheel off from the dead center. 80

It is usual to arrange above the magazine a hopper for a larger quantity of fuel from which the magazine is supplied. Whenever it is desired to stop the feed this hopper must be cut off and I have therefore 85 provided a novel construction of gate-operating mechanism therefor as follows: T is a slide or gate for closing an opening T' in the bottom of the hopper. U is a connecting rod pivotally attached to said slide 90 and extending longitudinally of the magazine, being connected at its outer end to a bell-crank lever U'. This lever is pivotally connected to a bearing V, which is attached to the frame C' for the doors C. 95 The actuating arm U² of the bell-crank normally extends laterally above the door opening and is socketed to receive a lever. The doors C are fashioned to close over the inwardly-projecting arm of the bell-crank, 100 one of the doors being cut-away for the outwardly-projecting portion of said arm. The arrangement is such that whenever it is desired to cut off the supply to the magazine, by inserting the lever in the socketed 105 bell-crank arm U² and drawing outward thereon, the sliding gate T will be shifted to close the opening T'.

As has been stated, the furnace is provided with a door B through which the fuel may be fed by hand. For operating this door I have provided an automatically-latching handle W, as shown in Fig. 1. This handle is pivotally connected at W' to the door, and has an outwardly-extending bent portion W² forming the handle grip and an inwardly-extending portion W³ which is hooked to engage a keeper W⁴ on the door frame. The portions W³ and W⁴ are beveled so that in the closing of the door they will automatically pass each other, permitting the latching of the hook into engagement with the keeper. When, however, the door is to be opened the lifting of the handle W² will disengage the hook and permit the door to be swung upon its hinges.

What I claim as my invention is:—

1. In an automatic stoking furnace, the combination with a furnace front, a magazine in rear thereof and a door controlling an opening through said front into said magazine, of a gate controlling the feed to said magazine, a rock-arm mounted on said furnace front, and an operating connection between said rock-arm and said gate entering through said door opening into said

magazine and arranged to clear said door in the closed position thereof. 30

2. In an automatic stoking furnace, the combination of a furnace front, a magazine in rear thereof communicating with an opening in said front, a door frame for said opening, a rockable member mounted on 35 said door frame having an actuated arm in a plane below the upper edge of said opening, a gate controlling the feed to said magazine, a pitman rod connecting said arm to said gate, and a door for closing said opening adapted to fit over said actuated arm. 40

3. In an automatic stoker furnace, the combination with a magazine and a door opening in the furnace communicating with said magazine, of a gate controlling the feed 45 to said magazine, and lever mechanism for operating said gate mounted outside of said magazine and extending through said door thereinto and arranged to clear said door in the closed position thereof. 50

In testimony whereof I affix my signature in presence of two witnesses.

EDWIN FITTS.

Witnesses:

ADELAIDE I. ADAMS,
JAMES P. BARRY.
